UNITED STATES PATENT OFFICE.

LORN CAMPBELL, JR., OF MINNEAPOLIS, MINNESOTA, ASSIGNOR TO UNITED STATES WELDING COMPANY, OF MINNEAPOLIS, MINNESOTA, A CORPORATION OF MINNESOTA.

BLOWPIPE.

Application filed May 3, 1920. Serial No. 378,358.

To all whom it may concern:

Be it known that I, LORN CAMPBELL, Jr., a citizen of the United States, residing at Minneapolis, in the county of Hennepin and 5 State of Minnesota, have invented certain new and useful Improvements in Blowpipes; and I do hereby declare the following to be a full, clear, and exact description of the invention, such as will enable others 10 skilled in the art to which it appertains to make and use the same.

My invention relates to what is known as blowpipes or torches of the character used to mix and burn various different gases, 15 such as acetylene and oxygen, and the particular object of the invention is the provision of improved means for adapting the blowpipe or torch for different kinds of work, or to different gases, or to different 20 conditions.

This improved means includes interchangeably usable gas mixers, and such interchangeable mixers may be applied in any convenient part of the blowpipe or torch. 25 The gas mixers may be interchanged simply by the substitution of the one for the other and without disturbing or disassembling the tip or any other part of the blowpipe or torch.

30 In accordance with my invention, I accomplish the above objects by the use of simple construction which is inexpensive to manufacture, convenient to use and strong and durable.

35 The invention is illustrated in the accompanying drawings, wherein like characters indicate like parts throughout the several views.

Referring to the drawings:

40 Fig. 1 is a vertical section taken centrally through the head, tip and mixer of the blowpipe, the part of the latter being in full; and

45 Figs. 2, 3 and 4 are views partly in elevation and partly in axial section showing gas mixers on a large scale removed from the head of the blowpipe.

The head 5 of the blowpipe has an internal threaded axial passage 6 and is provided at its upper end with a laterally projecting 50 shank 7, formed with a cylindrical chamber 8, adapting it to be secured to the outer tube (not shown) of the blowpipe, in the usual or suitable way. Passages 9 and 10 lead from the chamber 8 into the interior of 55 the head 5, the former being above the lat-

ter. The passage 9 has an enlarged internally threaded portion 9^a adapted to receive the end of the oxygen supply tube (not shown) but will usually extend through a larger acetylene conveying tube that will fit within 60 the chamber 8 and be rigidly secured to the shank 7 of the head 5.

The burner tip 11 has a threaded shank that is screwed into the threaded interior 6 of the head 5 and is provided with a beveled shoulder that engages a beveled surface of the head 5, at 12, making a gas tight joint.

The three interchangeable usable gas mixers illustrated in the drawings are externally alike, and each comprises a cylindrical body or plug 13, having an outer end 14 formed with a beveled surface 15. The cylindrical bodies of the gas mixers are externally threaded for engagement with the internal threads 6 of the head 5, but some of these threads are omitted on the outer end portions of the plug, so as to leave a smooth exterior surface 16 of reduced diameter, just inward of the beveled surface 15. Also, the 70 interior of the head 5 is left smooth or unthreaded for considerable distance near its upper end, so that when the mixer is screwed to position, its beveled surface 15 forms a 75 gas tight joint with the upper end of said head, and will leave an annular channel 17, surrounding the surface 16, into which the gas passage 9 directly opens. Also, the exterior surface of the body of each mixer 13 is reduced slightly in diameter at 18, so as 80 to leave an annular surrounding channel, into which the acetylene delivery passage 10 directly opens to the inserted mixer. 85

90 Preferably, and as shown, the lower and inner end of each mixer 13 is reduced and 95 telescoped through a pocket 11^a, formed in the inner end of burner tip 11.

99 Each gas mixer 13 is provided with a diametrical passage 19, the extremity of which, in the applied plug, will be in communication with the axial chamber 17 and hence with the oxygen gas passage 9.

100 The gas mixer shown, as applied in Fig. 1 is identical with the mixer shown in Fig. 4 and this mixer has an axial passage 20 of 105 constant diameter, and it further has a plurality of radial passages 21 that lead from the annular chamber formed by the reduced portion 18, to the intermediate portion of the axial passage 20. The said axial pas- 110

sage 20 at its upper extremities terminates in the diametrical passage 19, but at its lower extremities it delivers directly to the axial passage of the burner tip 11.

5 The plug shown in Fig. 3 is like that shown in Fig. 4, except that its axial passage comprises a relatively small upper portion 20^a and relatively large lower portion 20^b, the latter of which extends from the radial passage 21 to the delivery end of the mixer.

10 The mixer shown in Fig. 2 has radial ports 21^a of greater conducting capacity than the radial passages 21 of the other two mixers, and from these ports, an axial passage 22 extends to the delivery end of the mixer. A bushing 23 is inserted axially into the mixer outward of the ports 21^a. The bushing has radial openings 19^a that align 15 with the diametric passage 19, and at its inner end, it has a gas delivery passage 24 of much smaller diameter than passage 22.

15 As is already indicated, the gas mixers shown in Figs. 2, 3 and 4 are adapted for mixing acetylene and oxygen or other gases under different pressure or conditions. In the mixer shown in Fig. 2, oxygen gas under considerable pressure passes from bushing 23 through contact passage 24, thence 20 through the larger passage 22, thereby producing a suction which will draw the acetylene gas through ports 20^a, so that practically no pressure is required on the acetylene gas, in this type of mixer. Under certain 25 conditions and for certain purposes, this mixing action will give the best results and it has the advantage that the acetylene gas being carried at low pressure reduces to the minimum the danger incident to the use 30 of acetylene gas.

40 The mixer shown in Fig. 3 is adapted for use when the pressure on the acetylene and oxygen gases are equal or balanced, and this mixer has the advantage that back-firing cannot take place therein.

45 The mixer shown in Fig. 4 is adapted for use with low pressure oxygen gas, and high pressure acetylene gas. This mixer in Fig. 4 (shown also in Fig. 1) is desirable when welding certain alloy metals where there is danger of oxidizing the weld.

50 In the use of either of the mixers shown in Figs. 3 and 4, it will frequently happen that the pressure of the acetylene gas in the supply tank will be reduced to a point where the supply will not be properly afforded; the mixer shown in Fig. 2 may be substituted and then the residue of the low pressure, acetylene gas remaining in the tank can be 55 drawn out by suction produced when the said mixer (Fig. 2) is applied.

55 From what has been said, it will be understood that this invention is capable of variation as to detail of construction and arrangement of parts.

What I claim is:

1. A blowpipe comprising a head and having a gas mixer, a discharge nozzle tip secured therein, each being removable without disturbing any other part of the blow- 70 pipe.

2. A blowpipe comprising a head and having a gas mixer, a discharge nozzle tip secured therein, each extending therein from opposite ends and being in longitudinal 75 alinement.

3. A blowpipe having in combination a cylindrical head having a laterally extending connecting portion formed thereon having a chamber therein, said head having a threaded bore extending therethrough, and passages leading from said chamber thereto, a discharge tip secured in one end of said bore from one end, and a removable plug forming a gas mixer screwed into said bore, 80 from the other end. 85

4. A blowpipe comprising a head having a threaded bore therethrough and having a connecting chamber and passages leading from said chamber to said bore, a tip having a central bore and being screwed into the end of the bore in said head from one end thereof, and a mixing plug screwed into the bore in said head from the other end thereof, said plug having a central bore and having passages connecting the same with the passages in said head. 90 95

5. A blowpipe comprising a head having a cylindrical portion having a threaded bore extending therethrough and having a laterally extended portion having a chamber therein, and oxygen and acetylene passages from said bore communicating therewith, a tip screwed into said bore from one end having a longitudinal passage therethrough and a mixing plug screwed into said bore from the other end and having passages therethrough connecting said oxygen and acetylene passages with the passage in said tip. 100 105

6. A blowpipe comprising a head having a connecting chamber and an inclined hollow interiorly threaded portion, a one-piece gas mixing device screwed into said portion from one end, a tip nozzle screwed into said portion from the other end, each of the two latter devices being removable without disturbing the other. 110 115

7. A blowpipe having a head at its discharge end having a laterally extending projection adapted to be connected to oxygen and acetylene supply devices, a removable mixing plug adapted to mix said gases disposed in said head and insertable therein from one end, and a removable discharge nozzle tip disposed in and insertable in said head from its other end, said plug and tip being removable and insertable without disturbing any other part of said blowpipe. 120 125

In testimony whereof I affix my signature.

LORN CAMPBELL, JR.
